US0D1112040S

(12) **United States Design Patent** (10) Patent No.: **US D1,112,040 S**
(45) Date of Patent: ** Feb. 10, 2026

(54) **PORTABLE POWER STATION**

(71) Applicant: **SHENZHEN YIZU INNOVATION TECHNOLOGY CO., LTD.**, Shenzhen (CN)

(72) Inventors: **Xiaowei Leng**, Shenzhen (CN); **Zhiping Zhou**, Shenzhen (CN); **Yehai Pang**, Shenzhen (CN)

(73) Assignee: **SHENZHEN YIZU INNOVATION TECHNOLOGY CO., LTD.**, Shenzhen (CN)

(**) Term: **15 Years**

(21) Appl. No.: **29/938,022**

(22) Filed: **Apr. 18, 2024**

(51) LOC (15) Cl. **13-02**

(52) U.S. Cl. USPC **D13/103**

(58) **Field of Classification Search**

USPC D13/103, 104, 106, 107, 108, 109, 110, D13/112, 118, 119, 184, 199

CPC H02J 7/00; H02J 7/0042; H02J 7/0044; H02J 7/0047; H02J 7/0045

(57) **CLAIM**

The ornamental design for a portable power station as shown and described.

DESCRIPTION

FIG. 1 is a perspective view of a portable power station showing our new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an enlarged view of portion 10 shown in FIG. 3. The dash-dash broken lines in the drawings depict portions of the portable power station that form no part of the claimed design. The dot-dash broken lines represent boundaries of the enlarged portion and form no part of the claimed design.

1 Claim, 10 Drawing Sheets
